Primary Examiner — Ruth McInroy(74) *Attorney, Agent, or Firm* — RatnerPrestia**CLAIM**

The ornamental design for an exterior surface of a cyclone receptacle, as shown and described.

DESCRIPTION

FIG. 1 is a front perspective view of an exterior surface of a cyclone receptacle showing our new design;
FIG. 2 is a front elevation view thereof;
FIG. 3 is a left side elevation view thereof;
FIG. 4 is a rear elevation view thereof;
FIG. 5 is a right side elevation view thereof;
FIG. 6 is a top plan view thereof;
FIG. 7 is a bottom plan view thereof;
FIG. 8 is a front perspective view of a second embodiment thereof;
FIG. 9 is a front elevation view of FIG. 8;
FIG. 10 is a left side elevation view of FIG. 8;
FIG. 11 is a rear elevation view of FIG. 8;
FIG. 12 is a right side elevation view of FIG. 8;
FIG. 13 is a top plan view of FIG. 8; and,
FIG. 14 is a bottom plan view of FIG. 8.
In the drawings, broken lines indicate environmental structure or boundaries that form no part of the claimed design.
